COMBINATION LOCK

Millard F. Wise, Lemon Grove, Calif.

Application October 13, 1947, Serial No. 779,476

5 Claims. (Cl. 70—70)

1

My invention relates to a lock and key, more particularly to a combination lock and key therefor, and the objects of my invention are:

First, to provide a lock and key of this class which are very simple and easy to operate;

Second, to provide a lock and key of this class in which the lock thereof is very difficult to pick;

Third, to provide a lock of this class which may be partially locked and readily opened by a pin or the like when it is desired to latch a door or truck lift in certain position temporarily;

Fourth, to provide a lock of this class having a tumbler operated in combination with a pivoted latch whereby both said pivoted latch and said tumbler must be in certain position before the lock may be opened;

Fifth, to provide a lock of this class in which a pivoted latch may be readily operated in combination with a slide plate which prevents one end of said latch from becoming locked while the other end is being pivoted out of locked position, providing sufficient complexity of the lock in order to prevent unskilled persons from opening the same;

Sixth, to provide a lock of this class employing an intricate combination of locking operations which must be well known in order to open the lock;

Seventh, to provide a lock of this class which is very strong; and

Eighth, to provide a lock of this class which is very simple and economical of construction, efficient in operation, and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawing and to the characters of reference thereon forming a part of this application in which:

Figure 1 is a vertical sectional view of my lock; Fig. 2 is a rear elevational view thereof taken from the line 2—2 of Fig. 1 showing portions broken away and in section; Fig. 3 is a front elevational view of my lock; Fig. 4 is a front elevational view of the dial thereof; Fig. 5 is a side elevational view of the key for my lock; Fig. 6 is a similar view taken 90° to that as shown in Fig. 5; and Fig. 7 is a longitudinal sectional view taken from the line 7—7 of Fig. 6.

Similar characters of reference refer to sim-

ilar parts and portions throughout the several views of the drawing.

The frame plate 1, separable members 2 and 3, latch 4, latch bar 5, tumbler 6, tumbler shaft 7, face plates 8 and 9, spring 10, slide plate 11, strap 12, dial 13, key frame 14, key plunger 15, and the back plate 16 constitute the principal parts and portions of my lock and key.

The frame 1 is normally secured to the inner side of the separable member 2 which may be a door or a door frame, or the separable members 2 and 3 may be the body and lid of a trunk, or the like, as desired. The frame 1 is provided with a fulcrum 1a thereon projecting from the rear thereof over which the latch 4 is pivoted. This latch 4 is a resilient plate spring latch having latch pins 4a and 4b projecting through openings 1b and 1c in the frame plate 1. Corresponding openings 2a and 2b in the separable member 2 are provided through which the latch pins 4a and 4b respectively are adapted to extend. The spring 10 surrounds the latch pin 4b and bears against the inner side of the frame plate 1 tending to hold the latch pin 4a in the position as shown in Fig. 1 of the drawing. On the upper end of the frame plate 1 is a projecting latch pin 1d adapted to pass through the slot 6a in the drum shaped tumbler 6. This tumbler 6 is fixed on the shaft 7 which is journaled in the separable member 3 and back plate 16, as shown best in Fig. 1 of the drawing. The shaft 7 is provided with a bore 7a having internally opposed slotted portions 7b therein adapted to be engaged by projecting pins 14a of the key plunger 15, as shown best in Figs. 5 and 7 of the drawing. On the other end of the shaft 7 is a dial 13 having numerical designations as shown best in Fig. 4, which may be viewed through the opening 9a in the face plate 9. This face plate 9 is provided with a central opening 9b therein, through which the key, as shown in Figs. 5, 6 and 7 may be inserted to extend into the bore 7b of the shaft 7. The latch bar 5 is provided with a hinge portion 5a intermediate its ends, and is secured to the face and back plates 9 and 16 respectively at its upper end, and this latch bar 5 is vertically movable out of the strap 12 when the lock is unlocked for separating the separable members 2 and 3. The strap 12 is provided with a central opening 12a therein for the insertion of a pin to depress the latch pin 4a and remove it from interfering relation with the opening 5b in the latch bar 5 through which it is adapted to extend. The latch bar 5 is provided with a similar opening 5c in alignment with the latch pin 4b over which the slide plate 11

may be slidably shifted by means of the button 11a projecting at the front of the face plate 8. This button 11a extends through an elongated slotted portion 8a, and a correspondingly elongated slotted opening 5d in the latch bar 5. At the inner side of the lock I have provided a cover 17, not shown in Fig. 2 of the drawing which prevents the intricate mechanism of my lock from being tampered with, or damaged. It will be noted that this cover 17 is separated at 11a on a common line with the joinder of the separable members 2 and 3.

The operation of my lock and key is substantially as follows:

In order to open the lock, as shown in Fig. 1 of the drawing, the slide plate 11 is first forced upwardly into interfering relationship with the pin 4b on the latch 4 in order to prevent the same from passing into the opening 5c when the lower pin 4a is pushed backwardly by means of a nail or other object inserted through the opening 12a of the strap 12. The small diameter of the opening 12a accommodates only a small member so that when the latch pin 4a is forced backwardly out of interference with the opening 5b of the latch bar 5, the latch bar 5 may be slid upwardly into interfering relationship with the end of the latch pin 4a, thus permitting the latch bar 5 to be readily slidably separated from the separable member 2. When a person not versed in the use of my lock attempts to insert a pin through the opening 12a and pivot the latch member 4, he neglects to shift the slide plate 11 and in such a condition the latch pin 4b projects through the opening 5c of the latch bar 5, preventing slidable removal of said latch bar 5 from the strap 12. It will be noted that the slotted portion 6a of the tumbler 6 must be in alignment with the pin 1d on the frame 1 in order to separate the separable members 2 and 3. If the tumbler 6 is turned so that the slotted portion 6a is out of alignment with the pin 1d, the lock cannot be opened. In order to completely lock my lock, the slide plate 11 must be shifted downwardly, as shown in Fig. 1, permitting the spring 10 to force the latch pin 4a through the openings 2a and 5b in the separable member 2 and latch plate 5 respectively. Then the tumbler 6 must be turned so that the slot 6a is past the pin 1d providing double locking of the separable members 2 and 3 as desired. In order to turn the tumbler 6, the key as shown in Figs. 5 to 7, is forced into the bore 7a of the shaft 7, then the plunger 15 is forced downwardly as indicated by solid lines in Fig. 5, extending the pins 14a of the key frame 14 which are then extended into the slotted portion 7b in the side wall of the shaft 7. This places the pins 14a in shear, permitting the operator to turn the handle portion 14b of the key frame 14 for rotating the tumbler 6 as desired. It will be noted that the dial 13 provides an indexing means visible through the window 9a of the front plate 9 for identifying the original location of the dial in order to precisely set the slotted portion 6a of the tumbler 6 adjacent the pin 1d so that the tumbler 6 may be removed over the pin 1d when the latch bar 5 is released by the latch member 4. The hinge 5a of the latch bar 5 accommodates arcuate travel of one of the separable members 2 or 3 when they are forced apart.

Though I have shown and described a particular construction, combination and arrangement of parts and portions, I do not wish to be limited to this particular construction, combination and arrangement, but desire to include in the scope

of my invention the construction, combination and arrangement substantially as set forth in the appended claims.

Having thus described my invention, what I claim as new and desire to secure by Letters Patent is:

1. In a lock of the class described, the combination of a rotatably mounted drum shaped tumbler having a slotted portion in the side wall thereof, a pair of separable members, one of said separable members supporting said tumbler, the other of said separable members having a pin in connection therewith arranged to be positioned inwardly of said tumbler and pass through the slotted portion in the side wall thereof, a frame for said pin, a pivoted latch in connection with said frame having a latch pin on each end thereof and a latch bar pivotally connected with the separable member to which said tumbler is secured provided with openings therein adapted to be engaged by said latch pins of said latch member.

2. In a lock of the class described, the combination of a rotatably mounted drum shaped tumbler having a slotted portion in the side wall thereof, a pair of separable members, one of said separable members supporting said tumbler, the other of said separable members having a pin in connection therewith arranged to be positioned inwardly of said tumbler and pass through the slotted portion in the side wall thereof, a frame for said pin, a pivoted latch in connection with said frame having a latch pin on each end thereof and a latch bar pivotally connected with the separable member to which said tumbler is secured provided with openings therein adapted to be engaged by said latch pins of said latch member, a slide in connection with said latch bar adapted to be placed in interference with one of the holes in said latch bar for preventing one of said pins from entering the same.

3. In a lock of the class described, the combination of a rotatably mounted drum shaped tumbler having a slotted portion in the side wall thereof, a pair of separable members, one of said separable members supporting said tumbler, the other of said separable members having a pin in connection therewith arranged to be positioned inwardly of said tumbler and pass through the slotted portion in the side wall thereof, a frame for said pin, a pivoted latch in connection with said frame having a latch pin on each end thereof and a latch bar pivotally connected with the separable member to which said tumbler is secured provided with openings therein adapted to be engaged by said latch pins of said latch member, a slide in connection with said latch bar adapted to be placed in interference with one of the holes in said latch bar for preventing one of said pins from entering the same, a strap in connection with one of said separable members with which said frame plate is connected, adapted to surround the lower end of said latch bar.

4. In a lock of the class described, the combination of a rotatably mounted drum shaped tumbler having a slotted portion in the side wall thereof, a pair of separable members, one of said separable members supporting said tumbler, the other of said separable members having a pin in connection therewith arranged to be positioned inwardly of said tumbler and pass through the slotted portion in the side wall thereof, a frame for said pin, a pivoted latch in connection with said frame having a latch pin on each end there-

of and a latch bar pivotally connected with the separable member to which said tumbler is secured provided with openings therein adapted to be engaged by said latch pins of said latch member, a slide in connection with said latch bar adapted to be placed in interference with one of the holes in said latch bar for preventing one of said pins from entering the same, a strap in connection with one of said separable members with which said frame plate is connected, adapted to surround the lower extending end of said latch bar, a dial in connection with said tumbler at the outer side of said separable member arranged to indicate the relative position of the slot in said tumbler relatively to said pin.

5. In a lock of the class described, the combination of a rotatably mounted drum shaped tumbler having a slotted portion in the side wall thereof, a pair of separable members, one of said separable members supporting said tumbler, the other of said separable members having a pin in connection therewith arranged to be positioned inwardly of said tumbler and pass through the slotted portion in the side wall thereof, a frame for said pin, a pivoted latch in connection with said frame having a latch pin on each end thereof and a latch bar pivotally connected with the separable member to which said tumbler

is secured provided with openings therein adapted to be engaged by said latch pins of said latch member, a slide in connection with said latch bar adapted to be placed in interference with one of the holes in said latch bar for preventing one of said pins from entering the same, a strap in connection with one of said separable members with which said frame plate is connected, adapted to surround the lower extending end of said latch bar, a dial in connection with said tumbler at the outer side of said separable member arranged to indicate the relative position of the slot in said tumbler relatively to said pin, said strap having an opening therein aligned with one of said latch pins on said latch member adapted to admit a small object for depressing said pin out of interference with one of said openings in said latch bar.
